James Shetley Co.,
ATTORNEYS.

UNITED STATES PATENT OFFICE.

JOHN J. METZ, OF MEADVILLE, PENNSYLVANIA.

TRAIN-ORDER HOLDER.

Application filed November 23, 1921. Serial No. 517,337.

To all whom it may concern:

Be it known that I, JOHN J. METZ, a citizen of the United States, residing at Meadville, in the county of Crawford and State 5 of Pennsylvania, have invented new and useful Improvements in Train-Order Holders, of which the following is a specification.

My present invention pertains to train order deliverers, and it contemplates the 10 provision of a device for the purpose set forth through the medium of which a train despatcher may with but a slight amount of effort deliver to the trainman such orders as may be desired, without the necessity of 15 the engineer of the train reducing the speed of the train.

The invention further contemplates the 20 provision of a train order deliverer, that is simple and strong in construction, and one that is well adapted to withstand the rough usage to which similar devices are subjected.

The invention further contemplates the 25 provision of a device for the purpose set forth that may be handled with safety not only by the trainman but also by the despatcher.

Another object of the invention is the 30 provision of means whereby the hoop portion of the deliverer will be relieved of strain due to the impact of a passing trainman catching the said hoop portion.

The invention further contemplates the 35 provision of a train order deliverer that is so constructed and arranged that the impact above referred to tends to more firmly retain the message under the message clip.

The invention in all of its details will be 40 fully understood from the following description and claims when the same are read in connection with the drawings, accompanying and forming part of this specification, in which:

Figure 1 is a perspective view of the hoop and a portion of the handle thereof.

Figure 2 is a top plan view of a portion 45 of the hoop and showing the message clip in full lines in the position it assumes ready to receive the message, and showing the normal position of the clip in dotted lines.

Figure 3 is a longitudinal sectional view 50 of the hoop and clip together with the metal stamping.

Figure 4 is a sectional view of a portion 55 of the hoop and handle and showing the arrangement of the metal stamping with respect to the hoop and handle.

Figure 5 is a view illustrating the various elements of the hoop and handle connection thereof.

Figure 6 is a top plan view of the hoop, 60 its permanently secured handle portion, and the removable handle portion.

Figure 7 is a longitudinal sectional view of the connection of the removable handle of the deliverer and the handle portion of 65 the hoop.

Figure 8 is a modified form of a message clip that may be used in lieu of the preferred message clip.

Similar numerals of reference designate 70 corresponding parts in all of the views of the drawings.

My novel deliverer, comprises the hoop portion 1 that by preference is square-shaped in cross-section, and the said hoop portion 75 is formed of green bendable wood, and in fact all portions of the device that are formed of wood are preferably of the same green character in order to assure longer life to the device as a whole. 80

The said hoop portion terminates at one end in the square portion 9 and at its opposite end it is spliced and cut on a tapered swedge as indicated by 2. The fixedly secured handle portion 4 of the hoop is likewise provided with the spliced end that is formed in a tapered swedge portion 3 and the said ends 2 and 3 are arranged one upon the other and enter a ferrule of metal or other suitable material as shown at 5. This ferrule preferably is square at one end and at its opposite end is round in order to accommodate itself to the round surface of the hoop handle portion 4. The square portion of the ferrule is adapted to receive the 85 square material formed by the tapered swedge portions 2 and 3, and the said ferrule is secured on the hoop and handle thereof by means of rivets as shown in Figure 3. This ferrule is secured on the hoop and handle thereof by means of rivets as shown in Figure 3. These rivets also tend to hold the swedge 90 portions in proper position within the ferrule. 100

The metal stamping 6 is secured on the handle portion 4 and hoop portion 1 by means of small nails or rivets, and the said stamping is provided with the ears 7 through which the nails or rivets pass. Manifestly the stamping is provided with the raised portion 8 that receives the end portion of the hoop. The raised portion 8 is merely an eye and is so constructed that the loose end 105 of the hoop rests on the handle portion 4. 110

without binding and is adapted to move with respect to the handle portion 4 for an important purpose hereinafter set forth.

By reference particularly to Figure 5 it

- 5 will be seen that the message clip is preferably formed of wire as indicated by 10 and is provided at one end with the portion 11 that passes through the handle portion 4 and has a portion that bears against the 10 under side of the handle, and at its opposite end the clip is provided with the upstanding portion 12 that passes through the loose end of the hoop near its end 9. It will be seen by reference to Figure 2 that when it 15 is desired to place a message under the clip, the end 9 of the hoop is pulled slightly through the eye 8. The message is then inserted and because of the manner in which the clip is arranged on the handle portion 20 4 and the hoop portion 1, strain will be taken off of the hoop when the said hoop is caught by a passing trainman. Moreover the arrangement of the stamping on the hoop and the connection of the message clip prevents 25 the hoop end 9 from pulling out of the eye 8 of the clip when caught by the trainman. This is due to the fact that the end 12 of the clip will abut against the eye 8 of the stamping as will be apparent.
- 30 In order to permit a lady operator or towerman to deliver a message to a passing trainman without danger, I provide the automatic extension releasing handle 15 that is provided with the tapered swedge end 14 35 that bears on the correspondingly shaped portion 13 of the hoop handle 4. A socket 16 provided with the lips 17 is secured to the underside of the handle 15 by means of the rivets 19 and the said rivets are also adapted to retain a flat spring clip 18 on the upper end of the handle 15. The said handle 40 15, in order to assure ready use of the extension handle at all times may be provided with a socket and spring clip at each 45 of its ends, and if one is out of order the other will be ready for use.

In Figure 8 I have shown the message clip 20 that may be used in lieu of the clip 10. The said clip 20 straddles the underside 50 of one portion of the hoop and is secured to the opposite end of the hoop at either side of the eye 8. This construction also assists in relieving the pressure and strain imposed on the hoop during operation of the device.

In the practical use of the invention, the same may be used either with or without the automatic extension handle. The message 60 is placed under the clip and the trainman passes his arm through the hoop portion and either removes the device from the dispatcher's hand or from the extension handle as the case may be. The arrangement of the message clip at all times is such as to prevent 65 injury to the clip when the trainman

throws the hoop after receiving the message.

It will be apparent that the more strain that is placed on the hoop or loop portion of the device the tighter the message will be 70 retained on the hoop and in the clip and that the said clip will accommodate itself to any size of message and the larger or thicker the message the less strain that will be placed on the hoop when the device is in operation. 75

The device is light in construction and simple in operation and inexpensive to produce and contains no delicate elements such as are liable to become inoperative after a short period of use. 80

Having described my invention, what I claim and desire to secure by Letters-Patent, is:

1. In a train order deliverer, the combination of a hoop formed of bendable material, a plate secured thereto and having an eye therein through which a portion of the hoop passes; said eye being slightly larger than the diameter of the member, a message clip secured to the member and constructed 90 and arranged to relieve strain applied to the hoop.

2. In a device for the purpose set forth, the combination of a loop portion having a tapered end, a handle having a tapered end 95 and adapted to bear on the end of the loop portion, a ferrule secured to the end portions and the handle portion, a message clip secured to the handle portion and the loop portion, a member secured to the handle portion and loop portion, and having an eye through which the loose end of the loop portion passes and so constructed and arranged that a portion of the message clip abuts thereagainst at certain times to limit the movement of the loose end of the loop with respect to the eye, an extension handle having a tapered end a socket and a flat spring clip formed on the extension handle and adapted to bear thereon. 100

3. In a device for the purpose set forth, the combination of a loop portion, a handle portion secured thereto, and means arranged on the handle portion and loop portion for retaining said portions in proper position 115 with respect to each other; said means comprising a member secured to the handle and loop portion and having an eye through which the loose end of the loop portion passes, and a message clip arranged on the loop portion and adapted to limit the movement of the loose end of the loop portion with respect to the eye.

4. In a device for the purpose set forth, the combination of a hoop formed of bendable wood or other suitable material, a removable handle secured to the hoop, means for securing the handle and hoop to each other, a plate for retaining the loose end of the hoop to the handle portion, and a mes- 125

sage clip for preventing displacement of the hoop portion from the plate.

5. In means for the purpose specified, the combination of a handle, a tapered end formed on one end thereof, a hoop having a loose end and a tapered end adapted to bear on the tapered end of the handle, means for securing the said tapered ends to each other, a plate secured to the hoop and handle and 10 having lips that engage said members and also having an eye through which the loose end of the hoop passes, a clip constructed and arranged to receive a message and also prevent undue strain being placed on the

hoop, and also adapted to limit movement of 15 the loose end of the hoop with respect to the eye of the plate, an extension handle adapted to be removably secured to the hoop handle, and means for holding the said handles in proper position with respect to 20 each other.

In testimony whereof I have hereunto set my hand in presence of two subscribing witnesses.

JOHN J. METZ.
